(57) CLAIM

The ornamental design for a display screen or portion thereof with icon, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a display screen or portion thereof with icon showing a first embodiment of our invention; and, FIG. 2 is a front view of a display screen or portion thereof with icon showing a second embodiment of our invention. The broken lines showing of a portion of a display screen of a communications terminal illustrate environment and form no part of the claimed design.

1 Claim, 2 Drawing Sheets
